FORCE FEED LUBRICATOR

Clyde A. Parsons and Louis W. Drott, Detroit,
Mich., assignors to McCord Radiator & Mfg. Co.,
Detroit, Mich., a corporation of Maine

Application July 16, 1932, Serial No. 622,913

10 Claims. (Cl. 184—27)

This invention relates to force feed lubricators.

The main object of our invention is to provide a lubricator in which the pumping unit is in the form of a self contained single fixture having connected priming and delivery pumps so that the unit may be handled intact for insertion into and removal from the reservoir without disturbing any of the other units therein or the operating mechanism therefor or the setting or adjustment of the same.

Another object of our invention is to arrange the several elements of the priming and delivery pumps in axial alinement with the movable or operable element for the pumps in the form of a member located between and slidably supported by the piston and cylinder elements of said pumps, which elements are at the opposite ends of the unit.

A further object of our invention is to have this movable element form the cylinder and piston elements, respectively, for the delivery and priming pumps and by having a passage in said member provide means whereby the pumps are connected for the flow of oil from the priming pump to the delivery pump.

A further object of our invention is to locate the priming pump at the lower end of the unit and provide such pump with an intake port so disposed or arranged that priming of the unit will be immediately effected on operating the unit after refilling of the reservoir to a level above the port and thus prevent the unit from becoming air bound should the unit have been operated while the reservoir was dry.

Other and further objects of our invention will appear from the following specification taken in connection with the accompanying drawings, in which:

Fig. 1 is a front elevational view of our improved lubricator, parts being shown broken away and in section, respectively, for the purpose of illustration;

Fig. 2 is a vertical sectional view taken on line 2—2 of Fig. 1; and

Fig. 3 is a similar sectional view through the primary pump cylinder of the unit illustrating the manner in which air escapes from the cylinder when priming the unit.

The lubricator shown in the drawings is of the multiple unit type having a plurality of vertically disposed pumping units 1, 1 arranged in side by side relation in an oil containing reservoir in the form of a box-like tank or casing 2 common to all of the units. The latter extend downwardly into the reservoir through its top wall or

cover 3 which has individual openings to receive the units. The cover 3 has an upstanding boss structure 4 about the openings to support and provide seats for the units, there being set screws 5 at the boss structure to secure the units therein, as shown in Fig. 2. As the units are similar in construction and operation, a description of one will suffice for all.

The portion of the unit above the cover 3 is provided with a liquid containing chamber 6 through which extends an oil drop or globule guiding and conveying wire 7. The chamber 6 has glass or other transparent covered sight openings 8, 8, on opposite sides as shown. The wire leads from the inlet to the discharge end of the chamber where a nipple connects the unit to its oil conducting line, as in lubricators of this general character.

The pumping mechanism of the unit extends into the reservoir and comprises a pair of pump elements, arranged in axial alinement one above the other, and constituting the priming and delivery pumps of the unit. The delivery pump comprises a stationary piston element 9 and a movable cylinder element 10. The latter is slidably mounted on the piston element which is in the form of a tube secured to and extending downwardly from the part of the unit fitting in the boss 4. The cylinder element 10 is moved endwise on the tube by a spring 11 and a cam 12, respectively. The spring surrounds the cylinder 10 and normally urges the same downwardly against one end of a rock lever 13, the cam operating on the opposite end of the lever, as shown. The end of the lever at the cylinder 10 straddles it beneath an abutment or flange thereon as indicated in Fig. 2. Cam 12 and lever 13 are mounted on shafts 14, 15, respectively, supported in the reservoir 2 and extending lengthwise thereof to serve all of the units. Intermittent rotary movement is imparted to the cam shaft 14 by a ratchet mechanism comprising a pawl 16 on a driving shaft 17 and a ratchet wheel 18 on the cam shaft 14. The driving shaft 17, as shown in Fig. 1, may be alined with the cam shaft 14 and be oscillated back and forth through an arm (not shown) fixed to the shaft 17 and actuated from the drive of the engine or machine with which the lubricator is used. The ratchet wheel 18 is fixed to the cam shaft, while the pawl is carried by an arm 16a fixed to the driving shaft 17 as shown in Fig. 1.

The priming pump comprises a movable piston element 19 and a stationary cylinder element 20, the latter being at the lower end of the pump assembly and forced against the bottom wall of 110

the reservoir or tank 2 by a coiled spring 21 about said elements. Piston element 19 has an axial passage which connects at its opposite ends with the respective cylinder elements of the two pumps, there being ball check valves 22, 23 at opposite ends of the passage.

Cylinder element 20 is provided in its upright wall with an oil intake port or opening 24 which is opened and closed in the upward and downward movement of the piston element 19. Port 24 is located at or adjacent the end of the up-stroke of the piston and thus is disposed at the upper end or at the highest point of the oil receiving space of the cylinder. With the port so disposed and opening directly into the reservoir, as shown in Fig. 2, the oil in the reservoir may flow by gravity into the cylinder 20, as soon as the port 24 is uncovered by the piston. Any air in the cylinder at the priming of the pump will be displaced by the inflowing oil and escape directly and freely to the reservoir 2 through the open port. As the piston lowers, the port is closed and the oil in the cylinder 20 will be forced into the axial passage in the piston past the check valve 22. When this passage fills, oil will be delivered to the cylinder 10 on each downward or pressure stroke of the piston 19, and be discharged from the unit on each pressure stroke of the cylinder 10.

With the cylinder 20 located at the lower end of the pump unit, port 24 will be disposed closely adjacent the bottom of the reservoir and thus remain submerged in the oil until the reservoir becomes practically dry. Should the lubricator be operated when the reservoir is dry, that is, when the oil level is below the port 24, the pump unit while pumping some air will not become air bound because the intake port 24 will allow the pump to prime on refilling the reservoir. On refilling the reservoir, the cylinder 20 will instantly fill the moment the port 24 is uncovered by the piston and the pump will be primed, the air in the cylinder below the piston 19 being displaced into the reservoir by the incoming oil. The pump unit will thus soon become filled with oil on its first few strokes, and oil will be delivered from the unit with no ill effects caused by running the unit while dry. Any air in the unit ahead of the incoming oil will be forced out of the unit by the oil through the delivery line and it will not become trapped in the unit or in the line to interfere with or hinder the intended operation of the pumps.

The action of the cam 12 is as follows. When the parts are in the positions shown in Fig. 2, the priming pump is at the end of its intake stroke and the delivery pump is at the end of its compression stroke. When the flat side of the cam comes opposite the lever 13, the spring 11 moves the cylinder 10 downward on its intake stroke and the piston 19 downward on its discharge stroke. As the cam rotates the cylinder 10 is moved upward on its discharge stroke while the piston 19 is raised on its intake stroke. In the action described, a yieldable force is utilized for the delivery stroke of the priming pump while a positive power force is used for the delivery stroke of the other pump. The advantage of this is that the oil is supplied under a positive and known pressure to the part to be lubricated.

To permit manual operation of each unit 1 for the purpose of accelerating the oil flow therefrom without disturbing or changing the setting of the cams 12, I provide a plunger 25 extending downwardly into the reservoir at each unit

through the cover 3 as shown in Figs. 1 and 2. The lower end of the plunger is engageable with its rocker 13 through an abutment or lug 26 thereon at the end of the rocker opposite its connection with the pump unit. By forcing downward on the plunger the rocker may be moved to accelerate or increase the oil flow through the pumping mechanism of the unit.

Each unit by releasing its clamp or set screw 5 may be removed intact from the reservoir 2 without disturbing the other units or interfering with their operation. Moreover, any unit may be removed without requiring that the lubricator be disconnected from its source of power or stopping operation of the other units. This feature of removal is made possible by having the priming and delivery pumps in alinement and connected as a single fixture. Moreover, by having the rocker straddle the unit below the abutment thereon, the unit may be lifted intact from the reservoir without disturbing the rocker or its mounting in the reservoir.

The long bearing engagement between the piston and cylinder elements 9 and 10 of the delivery pump permit the development of a high pressure by such pump because the seal is of such extent to prevent leakage at high pressures. Thus the priming pump need only develop a pressure sufficient to deliver oil to the delivery pump especially at priming. The short section of the cylinder covered by the piston 19 of the priming pump when moving past the intake port is sufficient to provide the seal for this pump.

With the piston element 9 of the delivery pump at the upper end of the pumping unit, and the cylinder element 20 of the priming pump at the lower end of the unit, these elements may be held stationary by connection and contact respectively with the top and bottom walls of the reservoir 2. Moreover, with the arrangement of the parts, the piston element 19 of the priming pump and the cylinder element 10 of the delivery pump may be arranged between the other elements of the pumps and be connected in the form of a member common to the two pumps and operable by the spring 11 and rocker 13, respectively. With a member so arranged and slidably supported by the piston and cylinder elements of the pumps, the latter may be connected and alined to give the pumping unit the form of a self contained single fixture which is removable intact from the reservoir. As shown in the drawings the upper end of the member 10—19 is shaped to fit over the piston element 9 and form the cylinder therefor, while the lower end of the member 20 is shaped to extend into the cylinder element 20 and provide the piston therefor.

The parts of the unit constituting the pumps are connected together and held in assembled relation through the springs 11 and 21 as follows: A metal clip 27 connects the upper end of the spring 11 with the part 28 which supports the unit in the reservoir 1 from its top wall or cover 3, as shown in Fig. 2. Part 28, to which the piston element of the delivery pump is connected, fits in the boss 4 on the cover 3 and is secured on the boss by the set screw 5 as shown. The lower end of the spring 11 is connected by a similar clip 29 with the slide 10 which forms the cylinder of the delivery pump. Screws 30, 31 or equivalent means are employed to secure the clips to their respective supports, namely, the part 28 and the slide 10, as shown. A band-like member 32 connects the upper end of the spring 21 with the slide 10 through the piston element 19 of the

priming pump. A similar band 33 connects the lower end of the spring 21 to the cylinder element 20 of the priming pump. These bands are annular in form, or substantially so, and are shaped to fit over ribs or flanges on the parts which support them and the adjacent convolutions of the spring as shown in Fig. 2. The upper spring 11 is stronger than the lower spring 21 and is designed to maintain the slide 10 against the rock-lever 13 and to force the piston 19 of the priming pump into its cylinder 20 on the discharge stroke of said pump. The lower spring 21 is strong enough to maintain the cylinder 20 at all times against its abutment on the bottom wall of the reservoir 1. In the particular unit shown in the drawings, the upper spring 11 is designed for approximately 30 pounds, this being sufficiently strong to force the piston 19 against a pressure of approximately 500 pounds during the priming period after the pump has run dry. It is not necessary for the lower spring to be any stronger than that required to exert a force which will hold the cylinder 20 against its abutment and to overcome the pressure exerted by the vacuum on the piston employed, which in the particular assembly illustrated is not in excess of a maximum of 1 or 2 pounds.

The details of construction and arrangement of parts shown and described may be variously changed and modified without departing from the spirit and scope of our invention, except as pointed out in the appended claims.

We claim as our invention:

1. A pumping unit for force feed lubricators comprising a supporting member for the unit, priming and delivery pumps of the reciprocatory type in coaxial alinement with said member, said pumps each having relatively movable cylinder and piston elements, the stationary element of the delivery pump being directly connected to the supporting member, the movable elements of the pumps being connected together for movements in unison, a spring connecting the movable element of the delivery pump with the supporting member, and a spring connecting the elements of the priming pump.

2. A pumping unit for force feed lubricators comprising axially alined priming and delivery pumps of the reciprocatory type, each pump having a cylinder and a piston, the cylinder of the priming pump being located at the lower end of the unit, said priming pump cylinder being relatively stationary and having a closed lower end and an intake opening disposed thereabove adjacent the upper limit of the intake stroke of the cooperating piston element, and springs respectively interposed between the cylinders and pistons of the pumps for imparting relative movements thereto and for retaining the same in operative assembled relation.

3. A pumping unit for force feed lubricators comprising a supporting member for the unit, priming and delivery pumps of the reciprocatory type in coaxial alinement with said member, said pumps each having relatively movable cylinder and piston elements, the stationary element of the delivery pump being directly connected to the supporting member, the movable elements of the pumps being connected together for movements in unison, the cylinder of the priming pump being located at the lower end of the unit, said priming pump cylinder being relatively stationary and having a closed lower end and an intake opening disposed thereabove adjacent the upper limit of the intake stroke of the cooperat-

ing piston element, a spring connecting the movable element of the delivery pump with the supporting member, and a spring connecting the elements of the priming pump.

4. A pumping unit for force feed lubricators comprising axially alined priming and delivery pumps of the reciprocating type, one of the pumps having a relatively stationary piston and the other a relatively stationary cylinder, a rigidly connected cylinder and piston movable for cooperation with the relatively stationary piston and cylinder of said pumps, and spring means for respectively urging both cylinders outwardly relative to their cooperating pistons.

5. A pumping unit for force feed lubricators comprising axially alined priming and delivery pumps of the reciprocating type, one of the pumps having a relatively stationary piston and the other having a relatively stationary cylinder, a rigidly connected cylinder and piston movable for cooperation with the relatively stationary piston and cylinder of said pumps, a spring connecting the stationary piston and the movable cylinder of one pump for urging the cylinder outwardly, and a spring connecting the piston and cylinder of the other pump for retaining the cylinder against inward movement.

6. A pumping unit for force feed lubricators comprising a supporting member for the unit, priming and delivery pumps of the reciprocatory type in coaxial alinement with said member, each pump including a cylinder and a piston, the piston of the delivery pump being rigidly connected to the supporting member, the cylinder of the priming pump being relatively stationary and located at the lower end of the unit, the cylinder of the delivery pump and the piston of the priming pump being rigidly connected together for movements in unison, a coil spring interposed between the supporting member and the cylinder of the delivery pump for imparting movement in one direction to the rigidly connected cylinder and piston and for connecting the delivery pump cylinder with the supporting member, and a coil spring interposed between and connecting the piston and the cylinder of the priming pump and for retaining the cylinder of the priming pump against movement towards the support, said springs also serving to hold the pistons and the cylinders of the pumps in operative assembled relation.

7. In a force feed lubricator, the combination with a reservoir including a bottom, of a pumping unit located within the reservoir and comprising axially alined priming and delivery pumps of the reciprocatory type, each pump including cylinder and piston elements movable one relative to the other, the cylinder of the priming pump being engageable with the bottom of the reservoir, a spring interposed between the elements of the delivery pump for urging one of said elements downwardly, and a spring interposed between the elements of the priming pump for retaining the cylinder element against the bottom of the reservoir, and means for actuating the relatively movable elements of the pumps.

8. In a force feed lubricator, the combination with an oil reservoir having a bottom and a top, the latter having an opening, of axially alined priming and delivery reciprocating pumps removably mounted as a unit in the opening of said top and having the priming pump located adjacent the bottom of the reservoir, the priming pump having a cylinder resting against the bottom, the delivery pump having a piston rigidly

supported by the top, a rigidly connected piston and cylinder respectively associated with the priming pump cylinder and with the delivery pump piston, a coil spring disposed intermediate the cylinder and piston of the priming pump, a coil spring disposed intermediate the piston and cylinder of the delivery pump and having a greater tensile strength than the priming pump spring, and means located within the reservoir and engageable with the rigidly connected piston and cylinder to move the same against the resistance of the delivery pump spring.	thereto and for retaining the same in operative axial alignment.	80
9. A pumping unit for force feed lubricators comprising axially aligned priming and delivery pumps of the reciprocatory type, said pumps each having relatively movable cylinder and piston elements, the stationary elements of the pumps being at the opposite ends of the unit, the movable elements of the pumps being between the stationary elements and rigidly connected together for movements in unison, and springs respectively interposed between the cylinder and piston elements of the pumps for imparting relative movements	10. A pumping unit for force feed lubricators comprising a supporting member, priming and delivery pumps of the reciprocatory type below said member and in co-axial alignment therewith, said pumps each having relatively movable cylinder and piston elements, the stationary element of the priming pump being located at the lower end of the unit, the stationary element of the delivery pump being connected to and supported by said member, the movable elements of the pumps being interposed between the stationary elements and connected together for movements in unison, a spring connecting the movable element of the delivery pump with the support as afforded by said member, a spring connecting the elements of the priming pump, and a sight feed device above and supported by said member, the latter serving as a support for the pumps and the sight feed and having an oil passage connecting the pumps with the sight feed.	85
